[57] **CLAIM**

The ornamental design for a body for a doll, as shown and described.

DESCRIPTION

FIG. 1 is a front perspective view of a body for a doll showing my new design;

FIG. 2 is a front elevational view thereof showing my new design;

FIG. 3 is a rear elevational view thereof;

FIG. 4 is a left side elevation thereof;

FIG. 5 is a right side elevation thereof;

FIG. 6 is a top plan view thereof; and,

FIG. 7 is a bottom plan view thereof.

The broken lines showing the head and neck of the doll are for illustrative purposes only and do not form part of the claimed design.
